HYDROGENATION SYSTEM

Robert E. Wilson, Chicago, Ill., assignor to
Standard Oil Company, Chicago, Ill., a corpora-
tion of Indiana

Application November 28, 1930, Serial No. 498,579

2 Claims. (Cl. 196—53)

This invention relates to a combination liquid and vapor phase hydrogenation system and it pertains more particularly to a system for producing desulfurized, high-antiknock gasoline.

5 The object of my invention is to reduce the overall cost of gasoline production. A further object is to provide an improved means for heating the gases and vapors discharged from a liquid phase hydrogenation reaction chamber and for 10 simultaneously reducing the effective hydrogen concentration so that the vapors may be subjected to a vapor phase treatment at a higher temperature and lower partial pressure of hydrogen. A further object is to provide an improved, stable, 15 high-antiknock gasoline. Other objects will be apparent as the detailed description of my invention proceeds.

In a liquid phase hydrogenation process where a relatively large amount of the liquid is recycled 20 and a large excess of hydrogen is used, conditions are relatively unfavorable for the production of high antiknock gasoline. Under conditions of optimum through-put and minimum losses the product of a liquid phase hydrogenation step is 25 mainly an oil of boiling range similar to that of ordinary gas oil and which usually is not completely desulfurized if the original heavy charging stock was of high sulfur content. Some gasoline is formed but this is not of high antiknock quality. 30 These products are removed from the liquid phase hydrogenation as gases and vapors, and ordinarily must be cooled, condensed, and separated before being subjected to final vapor phase treatment for the production of high quality gasoline. 35 By highly superheating vapors of a light stock, such as high sulfur gas oil or naphtha bottoms, and introducing these superheated vapors into the mixture of gases and vapors leaving the liquid phase reaction chamber, I produce a mixture that 40 may be contacted with a catalyst at high temperatures and pressures to give a stable gasoline having a high antiknock value. The process may simultaneously convert, desulfurize and/or stabilize the light hydrocarbons.

45 In the accompanying drawing I have diagrammatically illustrated my improved system, parts of the apparatus being shown in section.

The charging stock may be any carbonaceous material, such as petroleum residuum, gas oil, 50 pressure tar, etc. (If coal or other solid material is used it should preferably be suspended in a liquid oil carrier). It may be conducted from the storage tank 10 through pipe 11, pump 12, pipe 13, mixer 14, heat exchanger 15, and pipe 16 to 55 preheater or pipe still 17. From the preheater the hot mixture is introduced by pipe 18 into liquid phase catalyst chamber 19. The liquid phase catalyst chamber is preferably a hollow cylindrical vessel and it is provided with a liquid discharge 60 pipe 20 and a gas and vapor discharge pipe 21,

the former being spaced from the top at a distance of about one-fourth to one-third the height of the tower and the latter being arranged at the top thereof. A pump 20A forces liquid from tower 19 back to the preheater 17 or to an intermediate 65 coil thereof. This pump and the feed pumps are both regulated in accordance with suitable indicators or by float controls (not shown) so that a constant liquid level is maintained in reaction chamber 19 and so that the amount of liquid 70 recycled through pipe 20 is approximately the same as the amount of fresh feed added through pipe 16. These features per se form no part of my invention and wide variations therefrom are permissible.

75 Many petroleum oils contain large amounts of sulfur and the gas oils which are produced from these oils are undesirable because of their high sulfur content. Also, many light hydrocarbons contain potential gum forming substances and 80 have to be stabilized by chemical treatment and/or rerunning. Usually straight run gasolines are characterized by a low antiknock value. My invention contemplates the use of any light hydrocarbons which it is desired to improve in 85 one or all of these respects, and in the preferred embodiment I use high sulfur gas oil or naphtha bottoms, in addition to the heavy oils treated as above described.

The light hydrocarbons are conveyed through 90 pipe 22, pump 23, pipe 24, mixer 25, heat exchanger 26 and pipe 27 to preheater 28, which is preferably a pipe still designed to vaporize the light oil and to superheat the vapors. The superheated vapors are conducted from preheater 28 95 by pipe 29, mixed with gases and vapors discharged from pipe 21, and introduced into a vapor phase reaction chamber 30. This chamber preferably contains a suitable catalyst 31 which is mounted on trays or screens 32. The 100 catalyst may be a mixture of chromium or molybdenum oxides or it may be any other catalyst known in the art. In the liquid phase chamber 19 the catalyst is preferably in finely divided or colloidal state and it is held in suspension 105 by the liquid and is recirculated therewith by means of pump 20A. In the vapor phase reaction chamber the catalyst is preferably in relatively large masses and is commonly referred to as a fixed catalyst. These features per se 110 form no part of my present invention and are not described in detail.

After the vapor phase hydrogenation, the mixture of gases and vapors leaves vapor phase chamber 30 through pipe 33 and is passed 115 through pipes 34 and/or 35 in amounts regulated by valves 36 and 37 to heat exchangers 15 and 26. The cooled mixtures are then conducted by pipes 38 and 39 to condenser coils 40 which 120 may be immersed in a suitable cooling fluid in

container 41, the fluid being circulated through the container by means of pipes 42. Gases and condensed vapors are discharged through pipe 43 into liquid separator 44 and the liquid product 45 (mainly gasoline) is withdrawn through pipe 46 and reducing valve 47.

Hydrogen and non-condensed vapors are discharged from the top of separator 44 through pipe 48 into scrubber tower 49, which contains 10 a suitable packing material 50 supported by screens 51. A scrubbing fluid 52, which is preferably a hydrocarbon oil such as a heavy kerosene, is collected at the bottom of tower 49, discharged through pipe 53 and reducing valve 54 15 to gas relief tank 55, conducted from the bottom of tank 55 through pipe 57, pump 58 and pipe 59 to distributing nozzle 60, and sprayed in the tower over the packing material countercurrent to the upward flow of gases. By this means 20 methane and light hydrocarbons are scrubbed out and the hydrogen is removed from the top of the scrubber through pipe 61, compressed by pump 62 and introduced by pipe 63 back into the system. Make-up hydrogen is added through 25 pipe 64 in amounts regulated by valve 65. Hydrogen is introduced into the charging stock and the light oil through pipes 66 and 67 respectively, the relative amounts being regulated by valves 68 30 and 69.

The entire apparatus is constructed to withstand operating pressures of 250-300 atmospheres, although I prefer to carry out the process at a pressure of about 200 atmospheres. The use of suitable alloy steels, insulating materials, entrainment arresters, etc. is of course, contemplated but these details are omitted from the drawing for the sake of simplicity.

The operation of my invention may be described as follows: the charging stock which may 40 be a heavy gas oil or pressure tar, is forced by pump 12 into the system at a pressure of about 200 atmospheres. For every cubic foot of charging stock I introduce about 5,500 cubic feet of 45 recycled hydrogen (from scrubber 49) and about 275 cubic feet of make-up hydrogen (from pipe 64). This mixture of oil and hydrogen picks up 50 some heat in exchanger 15 and is then heated to a temperature of about 850° F. in preheater 17. The liquid phase reaction chamber is maintained at about 850° F., the exothermic reaction 55 supplying substantially all of the heat that is lost by a properly insulated unit.

The amount of light oil introduced into the system may vary within relatively wide limits 55 and I prefer to use one or two parts of light oil to one part of charging stock. It should be particularly noted that the vapor phase treatment is carried out in the presence of the excess 60 hydrogen from the liquid phase reaction chamber so that large volumes of additional hydrogen are unnecessary. It is not necessary to add hydrogen with the light oil, but I may use up to about 250 volumes of hydrogen per volume 65 of light oil in order to provide more close control of conditions in the vapor phase preheater and chamber.

The mixture of light oil and hydrogen is heated 70 in preheater 28 to a temperature somewhat above 900° F. so that the final temperature of gases and vapors entering the vapor phase reaction chamber is higher than the temperature in the liquid phase chamber. The exact temperatures cannot be stated for all conditions and will depend to a large extent on the effectiveness of

insulation, since the hydrogenation reaction itself is exothermic.

I have found that to produce a high, anti-knock, stable, sulfur-free gasoline it is desirable to maintain a lower hydrogen partial pressure 80 in the vapor phase than is used in the liquid phase. It is also desirable to carry on the vapor phase reaction at a higher temperature. I obtain both of these desired conditions by superheating the light oil vapors, mixing them with 85 the gases and vapors leaving the liquid phase reaction chamber and introducing the total mixture into the vapor phase chamber. In this way I effect a great saving in hydrogen consumption and circulation, I effect a saving in the cost of 90 rerunning and/or converting light hydrocarbons, and I provide a stable gasoline with a high anti-knock value. It will be evident that the same final products could be obtained from the given heavy and light hydrocarbon raw materials by 95 suitable independent hydrogenation operations, carried out in separate apparatus and with no functional relation between the steps, but I find that by my improved process described herein this end is attained with a maximum thermal 100 efficiency and with a maximum recovery of the desired products.

The cooling, condensing and separating of my finished products are in accordance with conventional practice and will not be described in detail. The expression "destructive hydrogenation", as used in the following claims, is hereby defined as a pyrolytic conversion with hydrogen whereby heavy hydrocarbons or carbonaceous materials are converted into low-boiling products, 110 the reaction usually being effected at temperatures of about 850-1000° F. and pressures of about 200-300 atmospheres.

While I have described a preferred embodiment of my invention it is understood that I do 115 not limit myself to the details therein set forth except as defined by the following claims.

I claim:

1. The method of converting relatively heavy hydrocarbons into motor fuel of high anti-detonation value which comprises subjecting such hydrocarbons to destructive hydrogenation in liquid phase, removing gases and vapors from the liquid phase treatment, separately superheating other light hydrocarbon vapors to a temperature 120 above that maintained in the liquid phase treatment, mixing these superheated vapors with those obtained from the liquid phase treatment, and subjecting this mixture to destructive hydrogenation in vapor phase in the presence of a 125 hydrogenation catalyst, and at a higher temperature and under a lower partial pressure of hydrogen than those prevailing in the liquid phase treatment.

2. The method of converting relatively heavy 130 hydrocarbons into motor fuel of high anti-detonation value which comprises subjecting such hydrocarbons to destructive hydrogenation in liquid phase at a temperature of about 850° F. and under a pressure of about 200 atmospheres, 135 removing gases and vapors from the liquid phase treatment, admixing therewith separately superheated light hydrocarbon vapors whereby the mixture will have a temperature of at least 900° F. and a partial pressure of hydrogen lower than 140 that prevailing in the liquid phase treatment, and then subjecting this mixture to destructive hydrogenation in vapor phase at a temperature of at least 900° F.
